(57) **CLAIM**

The ornamental design for an infusion filter, as shown and described.

DESCRIPTION

FIG. 1 is a perspective view of an infusion filter according to one embodiment;

FIG. 2 is a top view thereof;

FIG. 3 is a bottom view thereof;

FIG. 4 is a left side view thereof;

FIG. 5 is a front view thereof;

FIG. 6 is a right side view thereof; and,

FIG. 7 is a rear view thereof.

In the drawings, the broken lines are for the purpose of illustrating portions of the infusion filter that form no part of the claimed design.

1 Claim, 7 Drawing Sheets
